CHARLES S. BANGHART, OF FLUSHING, NEW YORK, ASSIGNOR, BY MESNE ASSIGNMENTS, TO N-W EQUIPMENT CO., INC., OF NEW YORK, N. Y., A CORPORATION OF NEW YORK.

CHECK-PLATE FOR JOURNAL-BOXES.

1,136,640.

Specification of Letters Patent. Patented Apr. 20, 1915.

Application filed April 23, 1913. Serial No. 764,038.

To all whom it may concern:

Be it known that I, CHARLES S. BANGHART, a citizen of the United States, residing at Flushing, in the county of Queens, 5 State of New York, have invented certain new and useful Improvements in Check-Plates for Journal-Boxes, of which the following is a specification.

This invention relates to journals and 10 journal-bearings such as are employed on railway cars.

The invention has reference more particularly to check-plates for use in connection with such journal-bearings and is directed to the provision of a check-plate of an improved construction whereby numerous advantages are obtained including the prevention of excessive wear at the end of the axle, the lengthening of the useful life 15 20 of an axle and its journal-bearing, the reduction of breakage of the check-plates and the prevention of dust and dirt working into and oil working out of the bearing.

The axle commonly has its end received in 25 a journal-box for coaction with a journal-bearing located in the box and the extreme end of the axle extending beyond the bearing is provided with a circumferential groove. This groove is adapted to receive 30 and coact with a check-plate provided with a wall adapted to fit in the groove. Also these journal-boxes have been commonly provided with vertically disposed ways to receive the edges of the check-plates. The 35 check-plate as thus used has consisted of a metallic plate of rectangular shape having the central portion thereof cut away to the form of a semi-circle with parallel sides extending downwardly from the ends of the 40 semi-circle. Such a plate could be passed over the end of an axle, its side edges sliding in the ways in the journal-box and its inner edge entering the circumferential groove near the end of the axle. I have 45 found that by so shaping the check-plate that it will coact, not only with the ways in the journal-box and the circumferential groove in the axle, but also with the end of the axle, a construction is produced which 50 possesses important advantageous features in that it reduces wear and lengthens the life of the box in various other ways.

In accordance with my improvement, a 55 check-plate is made in the form of a single integral casting having the parts heretofore

provided in check-plates of this character and also having a wall which is adapted to extend over a substantial portion or all of the end of the axle. Such a check-plate may be constructed by employing two parallel 60 walls one of which is partially cut away, the latter wall being adapted to have its edge enter the circumferential groove in the axle and the other wall being adapted to lie against the end of the axle, one of these 65 walls being extended to form guides which move vertically in the ways formed on the interior walls of the journal-box.

I have illustrated the preferred embodiment of my invention in the accompanying 70 drawings, in which—

Figure 1 is a central vertical section of a journal-box, an axle projecting into the box and the improved check-plate upon the end of the axle; Fig. 2 is a horizontal section through the lower portion of the journal-box, looking upwardly toward the axle and check-plate, and Fig. 3 is a view of the check-plate.

Referring to these drawings, 4 indicates 80 a journal-box of the usual or any suitable construction, this having a detachable cover 5. The axle is shown at 6, its end being reduced and extended into the journal-box 4. The axle coacts with a suitable journal- 85 bearing 7 located within the box 4 in the usual manner. The axle 6 adjacent to its end is provided with a circumferential groove 8 for coaction with a check-plate. The journal-box 4 has ways 9 formed on the 90 inner sides of the side walls thereof opposite the circumferential groove 8 in the axle 6 when the latter is in its normal position.

The check-plate herein shown coacts with the circumferential groove 8 in the axle 6 95 and with the ways 9 on the side walls of the box 4 and also with the end of the axle 6. This check-plate is preferably a casting of brass or similar metal. It has two substantially parallel walls 10 and 11, the latter of 100 which is in the form of a flat plate and is adapted to lie against the end of the axle 6. The wall 10 has the central portion thereof cut away, the upper portion of this cut away part being semi-circular as shown in Fig. 105 3. The wall 10 as thus cut away is of such width that the edge thereof about the central opening will fit into the circumferential groove 8 in the axle 6. The two walls 10 and 11 are integrally united by a connecting 110

wall 12. The wall 10 at the center thereof extends downwardly from the connecting wall 12 a distance equal to the depth of the groove 8 in the axle. At the lateral edges 5 of the check-plate, ribs or guides 13 are provided adapted to enter within the ways 9 so as to hold the check-plate against excessive movement in the direction of the axis of axle 6. Fig. 3 is a view of the check-plate looking 10 at the inner side thereof. The wall 11 which is adapted to coact with the end of the axle shows through the opening in the wall 10. The wall 10 is shown as cut away to permit the axle 6 to project through it, 15 the upper portion of the opening in this wall 10 being semi-circular and of a diameter equal to the diameter of axle 6 at the bottom of the groove 8. The wall 10 is thickened slightly adjacent to the opening therein and the raised surface on the inner side of the check-plate formed by thus thickening wall 10 is finished so as to provide a smooth surface for coaction with the axle 6.

With this form of check-plate, a marked 25 reduction is effected in the amount of wear on the button at the end of the axle formed by the circumferential groove 8. It often happens that this button is worn off completely and heretofore axles so worn have 30 been unsuitable for further use. With the form of check-plate herein shown and described, such axles having the buttons thereof worn off may be continued in use. Again, 35 this form of check-plate offers more resistance to the end-thrust of the axle than the forms of check-plates now in common use and furthermore a substantial reduction is effected in the amount of breakage of check-plates when this construction is employed. 40 Another advantage secured by the use of check-plates as herein shown and described is that by the use of such plates the useful life of a journal-bearing is increased materially, this being due in part to the fact that 45 this form of check-plate prevents dust and dirt from working into the bearing and also prevents oil from working out of the bearing to a greater extent than the forms of

check-plates heretofore commonly employed. Such check-plate also prevents excessive end 50 motion of the axle which, if permitted, would result in unequal wear thereof in co-action with the journal bearing.

Having described my invention what I claim as new therein and desire to secure by 55 Letters Patent of the United States is:

1. The combination with a journal-box having vertical guideways on the inner sides of the walls thereof and an axle having one end extending beyond the bearing in the 60 box and provided with a circumferential groove adjacent its end and in line with said guideways, of a check-plate comprising two substantially parallel, integrally connected walls, one of which has the central portion 65 thereof cut away to form a segmental flange seated within said groove in the axle and the other of which walls extends over and in contact with the end of the axle, said first-named wall having laterally extending 70 ribs seated within said guideways in the journal-box, substantially as set forth.

2. The combination with a journal-box having vertical guideways on the inner sides of the walls thereof and an axle having one 75 end extending beyond the bearing in the box and provided with a circumferential groove adjacent its end, of a check-plate having laterally-extending edge-portions slidably seated within said guideways in the 80 journal-box, and having two substantially parallel integrally-connected walls, parallel to said edge-portions, one of which walls comprises a flat plate contacting the end of the axle, and the other of which comprises 85 a semi-circular flange seated within said groove in the axle, said walls being united by an integral connecting wall at the top thereof, substantially as set forth.

This specification signed and witnessed this 90 25th day of April, 1913.

CHARLES S. BANGHART.
